UNITED STATES PATENT OFFICE.

HERBERT W. BROWN, OF ASHLAND, OHIO.

DESIGN FOR A REPLACEMENT UNIT FOR HEADLIGHTS.

55,243.

Specification for Design.

Patented May 25, 1920.

Application filed December 23, 1919. Serial No. 347,019. Term of patent 14 years.

To all whom it may concern:

Be it known that HERBERT W. BROWN, a citizen of the United States, residing at Ashland, in the county of Ashland and State of Ohio, have invented a new, original, and ornamental Design for a Replacement Unit for Headlights, of which the following is a specification.

Referring to the drawing:—

Figure 1 is a front elevation of a replacement unit for headlights embodying my new design;

Fig. 2 is a rear elevation of the same; and

Fig. 3 is a side elevation of the same.

I claim:—

The ornamental design for a replacement unit for headlights, substantially as shown.

In testimony that I claim the foregoing as my own, I have hereto affixed my signature.

HERBERT W. BROWN.
